UNITED STATES PATENT OFFICE

ROBERT W. BIRCHFIELD, OF JOLIET, ILLINOIS, ASSIGNOR TO HEGGIE SIMPLEX BOILER COMPANY, OF JOLIET, ILLINOIS, A CORPORATION OF ILLINOIS

BOILER

Application filed October 29, 1924. Serial No. 746,548.

My invention relates to improvements in boilers of the kind particularly adapted for heating purposes, either hot water or steam.

The object of my invention is to provide a form of boiler which is particularly adapted to have the various sheets of which it is composed joined together at their edges by welding instead of rivets.

A further object of my invention is to provide a very simple self contained semi-portable form of boiler which has within its shell a substantially water jacketed smoke box through which the gases of combustion pass from the fire box to the return flues.

Another special object of my invention is to develop a relatively small boiler which can be made up of sheets of relatively small dimensions whereby the waste from larger sized boilers can be advantageously used. In connection with this latter feature the connecting of the sheets by welding instead of the old method of riveting is of prime importance as smaller scrap pieces can be made use of on account of the elimination of the overlapping joints necessary when they are joined by rivets.

In this present improved form of boiler, I provide an enclosed combustion space with a substantially cylindrical body portion above same and forming the top of the combustion space, within the main body part of the boiler I provide a closed space at the front end from which tubes lead through the main body part to the rear end where I provide a smoke box for connection to a stack.

In one form of my improved boiler the main body part is adapted to be extended to the rear to any desired extent to provide a greater length of gas travel from the grate to the stack for the purpose of economy in the extraction of heat from the combustion gases.

Another feature of importance resides in the adaptability of my improved boiler to the provision of water tubes passing through the upper part of the combustion space and which water tubes provide a convenient support for arch or roof fire bricks for control-

ling the flow of the gases from the fire to the flues.

My invention will be more readily understood by reference to the accompanying drawings forming part of this specification and in which:—

Figure 1, is a vertical, longitudinal, central sectional view of a boiler embodying my invention in one form;

Figure 2, is a vertical transverse, sectional view one half taken on the line 2—2 of Fig. 1 and the other half taken on the line 2^x—2^x of Fig. 1;

Figure 3, is a fragmentary view similar to Figure 1, showing another form of my improved boiler;

Figure 4, is a fragmentary, sectional view similar to Fig. 2, and taken one half on the line 4—4 of Figure 3 and the other half on the line 4^x—4^x of Figure 3;

Figure 5, is a horizontal sectional view on the line 5—5 of Fig. 1; and

Figures 6, and 7, are fragmentary horizontal sections on the lines 6—6 and 7—7 respectively of Fig. 1.

As illustrated in Figs. 1 and 2 my improved boiler comprises a unitary structure composed of preformed metal sheets joined together at their edges by welding and formed and arranged to provide a combustion or fire space 10 surrounded on all four sides by water legs 11 at front, 12 at the lateral sides and 13 at the back. Above the combustion space 10 is arranged the main body 14 of the boiler.

The upper part or steam space 15 of the main part of the boiler extends the full length of the boiler. In the lower portion of the main part of the boiler I arrange flues 16 extending forwardly from the rear end of the boiler to a front head 17 which is set back from the front end of the boiler to provide an auxiliary combustion space 18 for affording access of the gases of combustion to the forward ends of the flues 16. I provide a smoke box 19 at the rear end of the main part of the boiler through which the waste gases pass to the stack or chimney.

The boiler is set upon a base 20 which contains the usual grates, not shown.

The boiler is built up or made of an outer wrapper 21 which forms the upper half of the main part 14 of the boiler and the outer walls 22 of the side water legs 12 being bent or formed into U-shape for this purpose. Preferably the lower ends of the outer sheet 21 are flanged inwardly to close the lower ends of the side water legs 12 as shown at 23. At the ends of the boiler is a front end plate 24 extending from the bottom up to the auxiliary combustion space 18 and a rear end plate 24'. These end plates are preferably formed to fit within the ends of the preformed plate 21 and are welded thereto as shown at 25. These plates like the outer plate 21 are preferably flanged inwardly at their lower ends to close the lower ends of the front and rear water legs as shown at 26 and 27 respectively.

To form the inner shell or skin of the boiler I provide an inner U-shaped member 28 having vertical side parts 29 which form the inner walls of the side water legs 12 and the top 30 of which forms the crown sheet of the combustion chamber 10.

The crown sheet 30 preferably ends at its forward end in line with the front flue head 17 on the vertical dotted line 31 and the forward parts of the side walls of the main combustion chamber are preferably formed in the manner hereinafter more fully explained. The crown sheet 30 together with the upper part of the outer sheet 21 completes the circumference of the main part of the boiler.

The main combustion chamber is completed by a front plate 32 and a rear plate 33. The rear plate 33 fits within the rear end of the preformed inner sheet 28 and is welded at its top and side edges thereto as shown at 34 and at its bottom edge it is welded to the inner edge of the bottom flange 27 as shown at 35.

The front end plate 24 is provided with a fire door opening 36 and above its upper end the front end of the boiler is provided with a larger opening 37 giving access to the auxiliary combustion chamber 18 and to the forward ends of the flues 16. At the lower part of the opening 37 the metal of the front plate 24 is flanged inwardly as shown at 38 to close the top end of the front water leg 11. The front plate 32 of the combustion chamber 10 which forms the inner wall of the front water leg is welded at its top edge to the inner edge of the flange 38 as shown at 39. At its lower end this front plate 32 is welded to the inner edge of the bottom flange 26 as shown at 40 and at its side edges it is welded to the front edges of the sides 29 of the inner wrapper 28 as shown at 41. This inner end 32 is provided with a door opening 42 registering with the opening 36 in the outer end

plate and the door opening is completed by welding a sheet metal ring 43 between the inner and outer heads as shown at 44.

To complete the auxiliary combustion chamber 18 the forward flue head is welded at its lower edge to the front end of the crown sheet 30 as shown at 45 and the side portions 46 of this sheet are bent forwardly as shown in Figure 6 to form the sides of the auxiliary combustion chamber and the extreme edge portions are flanged out to meet the forward end of the outer shell at the sides of the opening 37 as shown at 47.

The forward end of the upper part 15 of the main part of the boiler is closed by a plate 48 which is formed at its upper edge to fit within the forward end of the outer shell 21 to which it is welded as shown at 47. The lower part 50 of this plate is bent back at a right angle to form the top wall of the auxiliary combustion chamber 18 and at its rear edge it is welded to the top edge of the front flue head 17 as shown at 51. Along the side edges of the bent back part 50 it is welded to the tops of the forwardly bent parts 46 of the front flue head 17.

The side edge portions 52 of the front inner head plate 32 are bent rearwardly to connect with the front edges of the side sheets 29 of the inner shell, and to which they are butt welded as shown at 53. The lower edges of the forwardly bent portions 46 of the forward flue sheet 17 are connected to the top edges of the bent back side edge portions 52 of the front inner sheet 32 as shown at 54 thus completing the inner shell of the boiler.

It is to be observed that the only relatively large sheets are the outer and inner wrappers, 21 and 28 and the rear outer head 25, and that all of the remaining parts are relatively small parts, particularly in a small house heating boiler and can be made out of the waste from the manufacture of larger boilers.

I provide a material addition to the heat absorbing surface of the combustion chamber 10 by providing a row of water circulating tubes 55 which extend from the front inner head 32 to the rear inner head 33 in the upper portion of the main combustion chamber 10. These water circulating flues may serve to support a fire brick arch or roof 56 for the combustion chamber 10 and arranged as indicated in dotted lines to hinder the direct flow of the gases of combustion from the fire to the auxiliary combustion chamber and cause them to first flow to the rear of the main combustion chamber.

In the form of my improved boiler shown in Figs. 3 and 4 I preserve all of the several features heretofore described and I

add to them a rearward extension 57 of the main portion 14 of the boiler. This extension is cylindrical and instead of the rear outer head extending to the top of the boiler 5 it is cut off at the lower part of the main part 14 of the boiler and the forward end of the extension is joined to the upper edge of the shortened rear head as shown at 58 and to the rear end of the upper part of the 10 outer shell 21 as shown at 59. This extension is closed at its rear end by a rear head 60 set in from the extreme end thereof to provide a smoke chamber 61. The smoke box is completed by an end plate 62 having a nozzle 63 for connection to a suitable 15 stack.

The boiler flues 16 extend clear through the main part of the boiler from the front head 17 to the rear head 60. By means of 20 this extension, which is very simple in character being cylindrical in shape I can make the flues any desired length to suit the particular conditions under which the boiler is to be used.

25 In this form I have shown the crown sheet 64 as curved downwardly instead of upwardly as in the form shown in Figs. 1 and 2, thus indicating that in producing my improved boiler I may use either form of 30 crown sheet.

As many modifications of my invention will readily suggest themselves to one skilled in the art I do not limit or confine my invention to the specific details of construction herein shown and described.

35 I claim:—

1. In a self contained boiler, a main combustion chamber in the lower part, an auxiliary combustion chamber at the front end 40 and above the main combustion chamber, an outer U-shaped shell, an inner shell formed to provide a crown sheet extending forward from the rear wall of the boiler to the rear end of the auxiliary combustion chamber and 45 to provide water walls at the sides and at the front and back of the main combustion chamber and at the sides of the auxiliary combustion chamber, a baffle wall below the crown sheet and in spaced relation thereto and extending from the front wall of the main 50 combustion chamber to a point spaced forward from the rear wall of the main combustion chamber, whereby the gases of combustion are directed forwardly from the rear 55 end of the main combustion chamber beneath the crown sheet and into the auxiliary combustion chamber, and flues extending from the auxiliary combustion chamber through the upper part of the boiler to the rear end 60 thereof.

2. In a boiler construction having an auxiliary combustion space at its front end connecting at its lower end with a main combustion space and giving access to fire flues 65 in the main part of the boiler, the front flue

sheet forming the rear wall of said auxiliary combustion space, the side edge portions of said sheet extending forwardly to form the side walls of said auxiliary combustion space and the extreme edge portions of the sheet bent to extend outwardly, and parallel with 70 the middle portion of the sheet to form part of the front head of the boiler.

3. In a boiler construction of the kind described having a main part of the boiler above a main combustion chamber, an auxiliary combustion chamber at the front end of the boiler connected at its lower end with the main combustion chamber, flues leading longitudinally through the main part of the boiler from the auxiliary combustion chamber, the sides of the auxiliary and combustion chambers being protected by water spaces in free communication with the main part of the boiler, and the top wall of the auxiliary combustion chamber and the upper 80 part of the front head of the boiler being made from a single piece of sheet metal.

4. In a boiler of the kind described, an outer U-shaped wrapper sheet, an inner wrapper sheet shorter than the outer sheet, 90 and an inner front head sheet having its side edge portions extending rearwardly and joined to the forward edges of the inner wrapper sheet as and for the purpose specified.

5. In a boiler of the kind described, an outer U-shaped wrapper sheet, an inner wrapper sheet shorter than the outer sheet, an inner front head sheet having its side edge portions extending rearwardly and joined to the forward edges of the inner wrapper sheet, an auxiliary combustion chamber above said turned back parts of the front head sheet, and the sides of said auxiliary combustion space being composed of side edge portions of the forward flue sheet turned forwardly and joined at their lower edges to the upper edges of said turned back portions of the front inner head as and for the purpose specified.

6. In a self contained boiler, a main combustion chamber in the lower part, the main combustion chamber provided with a fuel feed opening at the front end of the boiler, an auxiliary combustion chamber at the front end and above the main combustion chamber, an outer U-shaped shell, an inner shell formed to provide a crown sheet extending forward from the rear wall of the boiler to the rear end of the auxiliary combustion chamber and to provide water walls at the sides and at the front and back of the main combustion chamber and at the sides of the auxiliary combustion chamber, a baffle wall below the crown sheet and in spaced relation thereto and extending from the front wall of the main combustion chamber to a point spaced forward from the rear wall of the main combustion chamber, said baffle 125 flue

- wall being composed of a plurality of water tubes arranged in a substantially horizontal plane and refractory members supported by the water tubes, whereby the gases of combustion are directed forwardly from the rear end of the main combustion chamber beneath the crown sheet and into the auxiliary combustion chamber, and flues extending from the auxiliary combustion chamber through the upper part of the boiler to the rear end thereof, whereby the gases of combustion are directed forwardly from the rear end of the main combustion chamber.
7. In a self-contained boiler, a main combustion chamber in the lower part, the main combustion chamber provided with a fuel feed opening at the front end of the boiler, an auxiliary combustion chamber at the front end and above the main combustion chamber, an outer U-shaped shell, an inner shell formed to provide a crown sheet extending forward from the rear wall of the boiler to the rear end of the auxiliary combustion chamber and to provide water walls at the sides and at the front and back of the main combustion chamber and at the sides of the auxiliary combustion chamber, a baffle wall below the crown sheet and in spaced relation thereto and extending from the front wall of the main combustion chamber to a point spaced forward from the rear wall of the main combustion chamber, said baffle wall consisting of a plurality of water tubes extending longitudinally of the main combustion chamber from the front wall to the rear wall and arranged in a substantially horizontal plane, the forward portion of the tubes being covered by and supporting refractory members, whereby the gases of combustion are directed forwardly from the rear end of the main combustion chamber beneath the crown sheet and into the auxiliary combustion chamber, and flues extending from the auxiliary combustion chamber through the upper part of the boiler to the rear end thereof.
8. In a boiler construction having an auxiliary combustion space at one end connected at its bottom with a main combustion space and giving access to fire flues in the main part of the boiler, a sheet forming a flue sheet for said flues and the inner wall of said auxiliary combustion space and extending outwardly therefrom to form the side walls of said auxiliary combustion space, and the extreme edge portions of the sheet joined to the outer shell of the boiler.
9. In a boiler of the kind described, an outer U-shaped wrapper sheet, an inner U-shaped sheet and shorter than the outer sheet, an inner head sheet having its side edge portions turned inwardly and joined to the adjacent edges of the inner U-shaped sheet as and for the purpose specified.
10. In a boiler of the kind described, an outer U-shaped wrapper sheet, an inner U-shaped sheet shorter than the outer sheet, an inner head having its side edge portions extending inwardly and joined to the adjacent edges of the inner U-shaped sheet, an auxiliary combustion space above said turned inwardly edge portions, the inner wall of said auxiliary combustion space forming a flue sheet and the edge portions of said flue sheet extending outwardly and joined to the upper edges of the inwardly turned edges of the inner front head to form the sides of said auxiliary combustion space.
- Signed at Chicago, Illinois, this 10th day of October, 1924.
